UNITED STATES PATENT OFFICE.

LUTHER W. HOLLAND, OF PLEASANT HILL, MISSOURI.

LOCK.

1,147,092.

Specification of Letters Patent.

Patented July 20, 1915.

Application filed August 18, 1914. Serial No. 857,390.

To all whom it may concern:

Be it known that I, LUTHER W. HOLLAND, a citizen of the United States, residing at Pleasant Hill, in the county of Cass and State of Missouri, have invented a new and useful Lock, of which the following is a specification.

The present invention appertains to locks, and aims to provide a novel and improved door lock.

One of the objects of this invention is to provide a lock embodying a spring-pressed latch bolt adapted to be retracted by a knob-controlled roll-back, in combination with a novel key-controlled means for locking the latch bolt in projected position.

Another object of the invention is to provide a unique detent or holder coöperable with the latch bolt and adapted to hold the latch bolt in retracted position when the door is opened, and to release the latch bolt when the door is closed, so that the latch bolt will be sprung into its keeper without the necessity of slamming the door shut.

The present invention also contemplates a door lock of general improved construction, whereby the lock will be comparatively simple, durable, and inexpensive in construction, as well as being convenient, practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a side elevation of the lock, with the face plate removed and parts broken away. Fig. 2 is a horizontal or longitudinal section of the lock, with the latch bolt held in retracted position. Fig. 3 is a top view of the lock with the latch bolt released and engaged to the keeper. Fig. 4 is a fragmental detail illustrating the detent or holder. Fig. 5 is a reduced view of the key employed for locking and unlocking the latch bolt. Fig. 6 is a face view of a mortise lock embodying a modified form of detent for the latch bolt, the detent being illus-

trated in released position. Fig. 7 is a view similar to Fig. 6, illustrating the detent in position to hold the latch bolt in retracted position. Figs. 8 and 9 are sectional details taken on the lines 8—8 and 9—9 of Figs. 6 and 7, respectively.

In carrying out the present invention, there is employed a suitable case 1, which may be secured to the inner side of a door, or which may be fitted in a suitable mortise provided in the free edge of the door; whichever is desired. A latch bolt 2 has its beveled end slideable through the outer end of the case 1, and is provided with a pair of spaced longitudinal bars or arms 3 projecting toward but terminating short of the inner end of the case and provided at their inner or free ends, with angular lugs 4 with which the wiper arms 5 of the roll-back 6 are engageable. The roll-back 6 is journaled to the back and face plate of the case 1, and has the knob spindle 7 engaged therethrough, similar to an ordinary lock. The latch bolt is guided for sliding or reciprocatory movement within the case 1, by a pair of ribs 7^a provided upon the back of the case 1, and between which the latch bolt is movable.

In order to spring press the latch bolt to projected position when the same is free, the bars 3 of the latch bolt have an integral web 8 connecting them intermediate their ends, and the web 8 is provided with a pin or lug 9 projecting toward the face plate of the case 1, and a V-shaped spring 10 is provided with a coil 11 at its crotch, which engages over or embraces the pin 9, while the arms or end portions of the spring 10 are disposed between and bear against a pair of pins 12 projecting from the back of the case 1, above and below the latch bolt. The arms of the spring 10 have a spreading tension, whereby they tend to aline, and as a result, the spring 10 having its arms extended forwardly, will tend to project the latch bolt. This peculiar spring 10 will eliminate any side strains upon the latch bolt, and as a result, the latch bolt will move with the least amount of friction, which is highly desirable.

A second spring 13 may be employed jointly with or independent of the spring 10 for projecting the latch bolt, the spring 13 having a coil 14 intermediate its ends, which embraces a pin or lug 15 projecting from the back of the case 1, while the arms or terminal portions of the spring 13 bear against the rim of the case 1 and the pin or lug 9.

of the latch bolt for pressing the latch bolt outwardly. As indicated, either or both of the springs may be employed, as desired.

The locking mechanism for the latch bolt 3 includes a spindle or stem 16 journaled through the back and face plate of the case 1 within the slot or opening defined by the bars 3 of the latch bolt, and the spindle or stem 16 is formed within the case with a 10 rectangular or oblong tumbler or cam 17, while one end of the spindle 16 projects from the face plate of the case and is provided with a knurled thumb piece or knob 18. The tumbler 17 is provided adjacent the back of 15 the case 1, with a gear segment 19 extending from one side of the tumbler toward one end thereof, and the back of the case 1 is provided with a circular key-hole 20 for the reception of the key 21 which has its shank 20 provided with a bit 22 in the form of a spur gear. The bit 22 of the key is insertible through the opening or key-hole 20, whereby the bit 22 is adapted to intermesh with the segment 19 of the tumbler for oscillating or 25 rotating the tumbler or cam for locking and releasing the latch bolt as will hereinafter more fully appear.

The tumbler or cam 17 is yieldably held at its various positions, by means of a spring 30 23 which is provided with a coil or loop 24 intermediate its ends embracing one of the pins 12, and the said spring has its arms or terminal portions bearing against the rim of the case 1 and against the tumbler or cam 35 17, respectively. The tumbler is provided with a groove 25 extending along one side and along its ends, for the engagement of the corresponding arm or terminal portion of the spring 23, whereby the said arm of the spring 23 in bearing against the said side and ends of the tumbler or cam, will hold the tumbler in the positions desired.

A detent or holder 26 is provided for the latch bolt 2, and embodies a leaf spring 27 45 having its butt end secured to the face plate of the case 1, by means of a screw or securing member 28, and a second leaf spring or strip 29 resting against the outer side of the leaf spring 27 and having a slot 30 at its 50 butt end engaging the screw or clamping member 28. The free end of the leaf spring 27 is bent angularly, as at 31, to engage over the free or outer end of the latch bolt, when the latch bolt is retracted, and the edges of 55 the leaf spring 27 are provided with reflexed ears 32 engaging over the edges of the spring or strip 29 to hold the spring or strip 29 in place against the leaf spring 27, and so as to enable the spring or strip 29 to be adjusted longitudinally when the screw 28 is 60 loosened. The free end 33 of the spring or strip 29 projects beyond the free end of the leaf spring 27, to contact with or rest against the keeper 34 of the lock when the door is 65 closed.

In practice, the case 1 is secured to the door 35 in any suitable manner, and the door is provided with an opening or bore 36 leading to the key-hole 20 of the case from the outside of the door, while the finger-piece or knob 18 of the tumbler 17 is disposed upon the inside of the door, in order that the latch bolt may be readily locked and unlocked from the inside, while the latch bolt may only be locked and unlocked from the outside by means of the key 21, in the manner of the ordinary night latch. Due to the fact that the tumbler or cam 17 and its spindle or stem 16 are disposed in the median line of the latch bolt directly behind 70 and coöperable with the head of the latch bolt, it will be observed that the roll-back 6 and tumbler 17 will be disposed in horizontal or longitudinal alinement, so that the case may be reversed when the lock is employed as a right or left hand one, respectively. When the tumbler or cam 17 is at normal or idle position, as seen in Figs. 1 and 2, the latch bolt 2 may readily be retracted by turning the roll-back 6 as usual. 75

Supposing the latch bolt 2 to be released, then, when the door 35 is closed, the projecting end 33 of the detent 26 will rest against the keeper 34 to retract the angular portion 31 of the detent out of engagement with the latch bolt 2, and consequently the latch bolt will be free to spring into the keeper 34 for holding the door shut. As soon as the latch bolt is retracted and the door opened, the detent 26 being released from the keeper 34 which is secured to the jamb 37, will enable the angular portion 31 of the detent to move over the outer end of the latch bolt, while the latch bolt is retracted, and consequently the detent will hold the latch bolt 100 in retracted position as seen in Figs. 1 and 2, while the door is open. When the door is again closed, the detent 26 will be released by the keeper 34, to permit the latch bolt to snap into the keeper automatically. In this 105 manner, the latch bolt will be automatically held in retracted position while the door is open, and will be released as soon as the door is closed, to avoid the necessity of slamming the door shut as is not infrequently 110 necessary with the ordinary lock. To adjust the detent for properly accommodating the keeper 34 when the door shrinks away from the jamb, the screw 28 is loosened, and the spring or strip 29 is slid longitudinally 115 to the desired extent, whereby its protruding end 33 will coöperate properly with the keeper 34, and then the screw 28 is again tightened to hold the detent firmly in place. Although the detent is illustrated as being 120 on the exterior of the case, the same may be disposed interiorly, and may be constructed in various manners according to the circumstances. The outer end of the latch bolt is also beveled, in order that it may snap 125 130

into engagement with the keeper 34 in the usual manner, if necessary.

In order to lock the latch bolt 2 in projected position or in engagement with the keeper 34, the tumbler 17 may be readily turned from the inside through the medium of the knob 18 in order that one end of the tumbler may be swung outwardly to rest against the outer end portion or head of the latch bolt, 16 which will hold the latch bolt in projected position. Similarly, to swing the tumbler 17 to locking position from the outside, the key 21 may have its bit 22 inserted through the key-hole 30 to engage the segment 19 so that 15 when the key is rotated, the tumbler 17 will be rotated correspondingly for either locking or releasing the latch bolt. It is to be noted, however, that the segment 19 extends from one side to one end only of the 20 tumbler 17, whereby when the tumbler 17 is swung with the said end engaging the head of the latch bolt to hold the latch bolt projected, the tumbler cannot be released through the medium of the key 21 since the 25 segment 19 will be out of reach of the key bit 22. This will enable the latch bolt to be so locked from the inside, that a person on the outside even possessing a proper key, cannot unlock the latch bolt to enter the 30 dwelling or building. Thus, when the tumbler 17 is swung to position transversely of the latch bolt, the latch bolt may be readily retracted, and when the tumbler is swung to a longitudinal position, it will lock the 35 latch bolt in projected position. The tumbler may under all conditions, be manipulated from the inside of the door, but only can be manipulated from the outside under two conditions, namely, by means of the key 40 21, and when the segment 19 is in position to be engaged by the key bit 22 as above indicated.

In the variation illustrated in Figs. 6, 7, 8 and 9, a modified form of detent is applied 45 to a mortise lock. The mortise lock includes the case 1 arranged in a vertical plane and having the face plate 1^a through which the latch bolt 2 is slideable, the means for actuating and locking the latch bolt being the 50 same as illustrated in Figs. 1 and 2. The case 1 fits in a mortise in the door 35.

In applying the detent to the mortise lock, the face plate 1^a is provided with a recess or depression 40 surrounding the latch bolt 2 and providing the ribs or flanges 41 between the recess 40 and the side edges of the base plate 1^a. The flanges or ribs 41 are provided with slots 42 leading from the recess or depression 40.

60 The detent 43 is stamped from a plate of sheet metal, and is of U-shape, so as to enable the latch bolt 2 to pass therethrough. The arms of the detent are arranged horizontally at right angles with the vertical 65 plane in which the case lies. One arm, des-

ignated at 44, is disposed above the latch bolt 2, it being noted that the detent 43 is disposed flatly within the recess or depression 40, and the said arm 44 of the detent 43 is pivoted by means of a rivet or other pivot 70 member 45 whose axis is parallel to the latch bolt, to the face plate 1^a adjacent the upper end of the recess 40 or above the latch bolt 2. The other arm 46 of the detent 43 projects below the latch bolt 2, and is extended to form a tappet or finger 47 projecting through one of the slots or notches 42, it being noted that the detent is reversible in order that it may be properly positioned according to the direction in which 80 the door opens. The intermediate portion of the detent 43 is disposed at one side of the latch bolt 2, and is adapted to swing over the outer or free end of the latch bolt when the same is retracted, as seen in Fig. 9. 85 The lateral swinging or oscillatory movement of the detent 43 about its longitudinal axis and between the sides of the case is limited by means of a slot 48 provided in the free arm 46 of the detent, and a pin or 90 rivet 49 passing through the slot 48 and engaged to the face plate 1^a. The rivet or pin 49 being headed and engaged through the slot 48 will assist in holding the detent 43 within the recess or depression 40 to resist 95 the tendency of the latch bolt to shoot outwardly.

In order to swing the detent 43 over the free end of the latch bolt 2 when the latch bolt is retracted and when the detent is 100 free, a doubled wire spring 50 has one end engaged within the arm 44 of the detent 43 and has its other arm bearing against the flange or rib 41 opposite that one through which the tappet or finger 47 is passed. The 105 spring 50 will tend to swing the detent 43 over the end of the latch bolt 2, so as to project the tappet or finger 47 through the respective slot 42.

In the use of the modified form of the 110 detent, when the door 35 is closed, the tappet or finger 47 is arranged to strike the jamb, stop or other suitable part, so as to swing the detent 43 to the position illustrated in Fig. 6, when the door is closed. 115 This will enable the latch bolt 2 to shoot outwardly into engagement with the keeper (not shown.) As soon as the latch bolt 2 is retracted, and the door opened, the detent 43 will be released, and will be swung to 120 the position illustrated in Fig. 7, under the influence of the spring 50, and consequently the latch bolt 2 will be held in retracted position while the door is open, the tappet or finger 47 being projected through the 125 slot 42, in order that when the door is again closed, the latch bolt will be released as above intimated.

Particular attention is directed to the fact that the U-shaped detent 43 surrounds three 130

sides of the latch bolt, whereby the latch bolt and detent are assembled in a compact and effective manner.

Having thus described the invention, what is claimed as new is:—

1. In a lock, a latch bolt, and a rotatable rectangular tumbler coöperable with the latch bolt for holding it in projected position and having a gear segment extending from one side to one end thereof for the engagement of a gear bit.
2. In a lock, a case, a latch bolt mounted therein, and having an opening, a rectangular tumbler mounted within the said opening and having a spindle journaled through the case, the tumbler being rotatable for holding the latch bolt in projected position, the spindle having a knob at one side of the case, the other side of the case having a key-hole, the tumbler having a gear segment adjacent the last mentioned side of the case and extending from one side to one end of the tumbler, and a spring in the case adapted to bear against the ends and the side of the tumbler.
3. In a lock, a face plate having a depression and opposite slots leading from the depression, a latch bolt slideable through the face plate, a detent pivoted to the face plate and coöperable with the latch bolt to hold the same retracted, the axis of the pivot extending longitudinally parallel with the latch bolt, the detent being swingable between the sides of the depression and having an actuating portion to project through one or the other of the said slots, the detent being reversible, and a spring carried by the

detent to bear against one wall of the depression at either position of the detent and for swinging the detent into coöperative relation with the latch bolt.

4. In a lock, a face plate having a depression and opposite slots leading from the depression, a latch bolt slideable through the face plate, a U-shaped detent having one arm pivoted to the face plate, the detent being arranged within the depression and being coöperable with the latch bolt, the latch bolt being normally slideable through the detent, the other arm of the detent forming a tappet adapted to project through one or the other of the said slots, the detent being reversible, and a spring carried by the detent and adapted to bear against one wall of the depression at either position of the detent and for swinging the detent into coöperative relation with the latch bolt.

5. In a lock, a case arranged in a vertical plane, a horizontal latch bolt carried thereby, and a U-shaped detent having its arms disposed horizontally at right angles with the case and having one arm pivoted to the case, the detent being coöperable with the latch bolt and arranged normally so that it surrounds three sides of the latch bolt, and the other arm of the detent forming a tappet projectable beyond one side of the case.

In testimony that I claim the foregoing as my own, I have hereto affixed my signature in the presence of two witnesses.

LUTHER W. HOLLAND.
